CLAIM

The ornamental design for a control unit, as shown and described.

DESCRIPTION

FIG. 1 is a top perspective view of the control unit;
FIG. 2 is a top view of the control unit thereof;
FIG. 3 is a bottom view of the control unit thereof;
FIG. 4 is a front view of the control unit thereof;
FIG. 5 is a rear view of the control unit thereof;
FIG. 6 is a left side view of the control unit thereof; The right side view of the control unit is a mirror view of the left side view;
FIG. 7 is a left side view of the control unit thereof in a bent configuration; The right side view of the control unit in the bent configuration is a mirror view of the left side view;
FIG. 8 is an enlarged detail view of the area 8 as shown in FIG. 3;
FIG. 9 is an enlarged detail view of the area 9 as shown in FIG. 3;
FIG. 10 is an enlarged detail view of the area 10 as shown in FIG. 3;
FIG. 11 is an enlarged detail view of the area 11 as shown in FIG. 3;
FIG. 12 is an enlarged detail view of the area 12 as shown in FIG. 3;
FIG. 13 is an enlarged detail view of the area 13 as shown in FIG. 4;
FIG. 14 is an enlarged detail view of the area 14 as shown in FIG. 5;
FIG. 15 is an enlarged detail view of the area 15 as shown in FIG. 5;
FIG. 16 is an enlarged detail view of the area 16 as shown in FIG. 5;
FIG. 17 is an enlarged detail view of the area 17 as shown in FIG. 6;
FIG. 18 is an enlarged detail view of the area 18 as shown in FIG. 7;
FIG. 19 is an enlarged detail view of the area 19 as shown in FIG. 7; and,
FIG. 20 is an enlarged detail view of the area 20 as shown in FIG. 7.
In the drawings, the broken lines depict a portion of the control unit which form no part of the claim.
